UNITED STATES PATENT OFFICE.

CHARLES R. FOARD, OF ELKTON, MARYLAND.

FOOT-MEASURING DEVICE.

Application filed May 31, 1928. Serial No. 281,717.

The present invention relates to measuring devices and has for its principal object to provide means for the measuring of a person's foot in order to determine the proper size of shoe to be worn.

A further object of the invention is to provide a measuring device of this character which is adjustable as to width and length for accurately measuring the size of the foot for fitting a shoe thereon.

A further object of the invention is to provide means for holding the measuring device so as to arrange the same in a compact manner.

Another object of the invention is to provide a device of this character of a simple and practical construction, which is efficient and reliable in performance relatively inexpensive to manufacture, and otherwise well adapted for the purposes for which the same is intended.

Other objects and advantages reside in the special construction and combination of the various elements comprising the invention, reference being had to the accompanying drawings, forming a part hereof, wherein:

Figure 1 is a top plan view.

Figure 2 is a transverse sectional view, and

Figure 3 is a fragmentary longitudinal sectional view through the connection for the various sections of the device.

Referring now to the drawing in detail, wherein for the purpose of illustration I have disclosed a preferred embodiment of my invention, the numeral 5 designates a main base member for obtaining measurements of the forward portion of the foot, and the numeral 6 represents an extension from the rear edge of the base member and which extension is provided for measuring the heel of the foot.

The extension 6 is hingedly connected to the main base section 5 by a flexible strip 7 secured in overlapping relation to the underside of the abutting edges of the extension and the base section. Adjacent the extreme forward edge of the main base section 5 is a longitudinally extending slotted opening 8, above which is disposed an adjustable stop 9 also having a longitudinally extended slotted

opening 10 formed therein and through which an attaching bolt 11 is inserted with one end of the bolt extended through the opening 8. The end of the bolt protruding from the under side of the base 5 is formed with the head 12 and the opposite ends of the bolt protruding from the upper edges of the

stop 9 is threaded and adapted to carry a nut 13 for securing the stop in longitudinally adjusted position upon the base. The inner end of the stop 9 is formed with an upwardly extending flange 14, against which the toe of the foot may be placed for indicating the measurement at the smaller end of the foot. At the side edges of the base 5 are also arranged a pair of spaced apart stops indicated generally at 15, the stop at each side of the base comprising a pair of stop plates 16 disposed in slightly spaced parallel relation and provided at their inner ends with an upwardly extending flange 17, connecting the stop plates for movement as a unit, and also forming a basis for the measurement of the width of the foot. Each of the top plates 16 are provided with slotted openings 18, extending inwardly from the outer edges of the plate, and within which openings is inserted a bolt 19 with one end extended through a forwardly and inwardly inclined opening 20 formed in the base 5. The bolts 19 likewise have their lower ends provided with heads and with a tightening nut 21, threaded on the upper end for securing the plate in adjusted position with respect to the base. As clearly illustrated in Figure 1 of the drawing, the forwardly and inwardly inclined slotted opening 20 is rotated with each of the stop plates 16 or disposed in spaced parallel relation. The pair of bolts 19 disposed at the opposite sides of the base also have one end of a strap 22 attached thereto, said attached end of the strap being interposed between the base 5 and the stop plates 16. The strips 22 at the opposite sides of the base are adapted to extend over the foot and may be adjustably secured to each other by means of buckles 23 or the like. Disposed rearwardly of the straps 22 is also arranged a strap 24 adapted to extend over the instep of the foot whereby to firmly secure the foot in position upon the base.

At the rear end of the extension 6 is also arranged a stop plate 25, similar to the front stop plate 9 and likewise having a longitudinally extending slotted opening 26 disposed therein above a similar opening 27 formed adjacent the end of the extension 6. A retaining bolt 28 is inserted through the slotted openings 26 and 27 for securing the stop plates 25 in adjusted position of the extension and the forward edge of the stop plate is likewise provided with an upwardly extending flange 29 forming the basis for the

measurement at the heel of the foot. It will be apparent that upon securing the device in position on the foot, by the straps 22 and 24, as indicated, and properly adjusting the toe and heel stop plates, as well as the side stop plates to the size of the foot, that an accurate measurement thereof may be made. The device is admirably adapted for use by persons remote from a store, at which the purchase 10 of shoes of a particular size may be made, and by employing my invention, an exact measurement of the foot may be made, and the device shipped to the factory for the purpose of making shoes from the size indicated 15 by the measuring device.

By hingedly connecting the separate sections of the base, the device may be folded in a compact manner for shipping purposes.

It is obvious that the invention is susceptible of various changes and modifications, without departing from the spirit or scope of the invention or sacrificing any of its advantages, and I accordingly claim all such forms of the device to which I am entitled.

Having thus described my invention, what I claim as new is:

1. A foot measuring device comprising a sectional base, the sections being hingedly connected to each other, foot attaching straps 30 carried by the base, and stop plates adjustably mounted at each end and at each side of said base.

2. A foot measuring device comprising a

sectional base, the sections being hingedly connected, foot attaching straps carried thereby, toe and heel stop plates arranged at opposite ends of the base and adjustable longitudinally thereof, means for securing said plates in adjusted position, a pair of stop plates disposed at opposite sides of the base 40 and cooperating means for the base and the plates providing for transverse and longitudinal adjustment of said plates.

3. A foot measuring device comprising a sectional base, the sections being hingedly connected, a foot attaching strap fixedly carried by the base, toe and heel stop plates disposed at opposite ends of the base and adjustable longitudinally thereof, means for securing said plates in longitudinally adjusted position, a pair of stop plates disposed at opposite sides of the base, each of said plates having an inwardly extended slotted opening formed therein, and said base having a forwardly and inwardly inclined slotted opening formed therein in registry with the opening of the plate, retaining means for the plate inserted through said opening and adapted for movement longitudinally of the slot, whereby to secure the plate in adjusted position with respect thereto, and a foot attaching strap having its opposite ends attached to said retaining means disposed at the opposite sides of said base.

In testimony whereof I affix my signature,

CHARLES R. FOARD.
